UNITED STATES PATENT OFFICE

JOSEPH H. COPE, OF DENVER, COLORADO

EXTENSION HAYSTACKER

Application filed May 13, 1929. Serial No. 362,664.

This invention relates to improvements in extension haystackers of the type described and claimed in my copending application Serial No. 247,179, filed January 16, 1928.

5 It is the object of this invention to produce a haystacker of the extension type which shall be so constructed that the parts that are subjected to severe strains will be so made that the timbers cannot split and which shall be 10 provided with means for limiting the throw of the stackerhead and for stopping the same without subjecting the pivots about which the stackerhead moves to the severe strains to which they are subjected in the usual construction.

15 It is a further object of this invention to provide an improved connection between the stackerhead extension frame arms and the lifter bars that will obviate the danger of 20 splitting the arms and which will also permit the arms to be twisted so as to properly adjust them.

The above and other objects which will 25 become apparent as the description proceeds are attained by means of the construction and an arrangement of parts that will now be described in detail, reference for this purpose being had to the accompanying drawings in which the preferred embodiment of the invention 30 has been illustrated and in which:

Fig. 1 is a top plan view of the improved extension stacker;

Fig. 2 is a side elevation of the stacker shown in Fig. 1;

Fig. 3 is a side elevation showing the stacker with the stackerhead in elevated position;

Fig. 4 is a section taken on line 4-4, Fig. 3;

Fig. 5 is a section taken on line 5-5, Fig. 40 2; and

Fig. 6 is a section taken on line 6-6, Fig. 2.

The improved stacker forming the subject 45 matter of this invention is provided with a frame having two spaced parallel runners 1, whose rear ends are connected by a transverse frame member 2, and which are further connected by means of transverse bars 3, 4 and 5. Corner posts 6 are provided 50 at the rear end of the frame and each of

said corner posts consists of two spaced parallel members secured to opposite sides of the corresponding runners. Braces 7 have their upper ends connected with the corner posts and extend diagonally at an angle of 45 degrees and have their lower ends notched into the upper edge of the runners in the manner indicated by numeral 8. Steel bars 9 are connected to each side of each corner post brace and extend over the runners to which they are secured by bolts or rivets in the manner shown quite clearly in Figs. 2 and 3. Short braces 10 extend from the underside of the corner post braces to the runners and have their lower ends notched into the runners as indicated by reference numeral 11. These braces, like braces 7, are provided with steel bars 9 by means of which they are anchored to the runners. Angles 12 are placed in the corners where the braces 10 intersect the braces 7 and are held in place by means of bolts that extend through the braces 7 and through the steel bars 13 located on top of these braces. This construction prevents braces 7 from splitting in planes perpendicular to the surfaces shown in Figs. 1 and 2. Secured to opposite sides of braces 7 are washers 14 that are provided with hubs 15. A bolt 16 extends through each of the braces 7 and through the openings in hubs 16. A washer 17 is located between the head of bolts 16 and the corresponding outer end of the hub on one of the washers. The upper end of brace 18 is provided with an opening through which the bolt 16 passes, in the manner shown in Fig. 4 and the lower end of this brace is secured to the transverse bar 3 by means of a bolt 19. The stacker frame arms 20 are provided at their lower ends with steel bars 21 which 90 embrace the braces 7 and are provided with openings for the reception of the hubs 15, all as shown in Fig. 4. The hubs 15 become the pivots about which the stacker arms rotate and when the nuts 22 on bolt 16 are drawn up tight, the braces 7 cannot split in planes perpendicular to the axes of bolt 16. The construction just described is a very substantial one and practically all danger of the braces 7 splitting is obviated by the clamp-

55

90

100

ing action of the bolts connecting the angles 12 to the steel bar 13 and by the action of bolts 16. The notched construction where the ends of braces 7 and 10 connect with the 5 runners 1 combines with the steel bars 9 results in a construction which is exceedingly rigid and which, therefore, does not readily become loose due to the heavy strains to which the parts are subjected. The upper 10 ends of the corner posts 6 are connected by means of a bar 23 which extends parallel to the bar 2 and are further braced by means of diagonal braces 24 whose upper ends are connected with the center point of bar 23 15 and whose lower ends are connected to the runners by means of bolts 25. Short diagonal brace members 26 extend from near the center of bar 2 to the outer ends of bar 3 to which they are connected by means of bolts 20 27. A pulley 28 is connected with the upper ends of the braces 24 and a cooperating pulley 29 is connected with the transverse bar 2, while still another pulley 30 is connected with the pivot about which pulley 28 rotates 25 by means of straps 31. As the actual construction of these pulleys and the guides with which they are provided has been shown and described in detail in the copending application above identified they will not be more 30 completely described in this application than is necessary for the purpose of properly explaining the operation of the device. An A frame comprising two rigid members 32 whose lower ends are pivotally connected at 35 33 to the inside of the runners 1 are connected intermediate their ends by means of transverse bars 34 and have secured between their upper ends two straps 35 and a pulley 36. This pulley is provided with a cable 37. Rods 38 have their upper ends connected with the straps 35 and have their lower ends connected to the bolts 39 in the manner shown in Fig. 6. The stackerhead lifting arms 20 are connected by means of 40 transverse bars 40 and 41. The bar 40 is located in between the stackerhead arms 20 and is secured to the latter by means of angle braces 42 in the manner shown in Fig. 1. The bar 41 extends underneath the arms 20 and is secured to the latter by means of bolts 43. Straps 44 are secured to the opposite sides of arms 20 and extend upwardly above the 45 tops of the stackerhead extension arms 45. A casting 46 is secured between the upper ends of the straps 44 by means of a bolt 47, and secured to the underside of this casting is a bumper spring 48 to which reference will hereafter be made. Braces 49 extend diagonally from the outer ends of straps 44 and are secured to the arms 20 by means of bolts or rivets 50. Diagonal braces 51 extend from near the outer ends of the transverse bar 41 to points near the center of the transverse bar 40 and are secured to the latter by 55 means of bolts 52. The other ends of bar 51 are secured to the bar 41 by means of bolts 53, which pass through openings in the flattened perforated heads of bolts 39. Brackets 54 are secured to the ends of bars 41 by means of bolts 55 and these brackets are perforated 60 so that bolts 39 may pass through them. These bolts also pass through strap 44 and through the arms 20 and are provided with nuts 56 and 57 which can be adjusted longitudinally of the bolt and which therefore 65 serve to twist the arms 20 so as to properly locate them in case this becomes necessary. The clamping action of nuts 56 and 57 also serves to prevent the arms 20 from splitting. The tension in the rods 38 is resisted by the 70 bolts 39 and by the brackets 54 and therefore the splitting action which might result if rods 38 were connected directly with the arms 20 is avoided. 75

The stackerhead consists of a plurality of 80 bars or fingers 58 whose rear ends are connected by means of a transverse bar 59 and which are further connected by means of a transverse bar 60. Vertical fingers 61 are secured to the fingers 58 by means of bolts 62 85 and these are braced by means of diagonal braces 63. The stacker head is attached to the front ends of the stacker-extension arms 45 whose front ends are secured to the bar 60 by means of bolts 64. These extension 90 arms are located between the bars 44 and are provided near their other end with U-shaped steel clamps 65 that encircle the arms 20 and which serve as guides for bars 45. Bars 45 are provided with spaced openings 66 that 95 are adapted to receive pins 67 which, of course may be shifted from any set of openings to any other set as may be desired. Each of bars 45 are also provided with a transverse bar 68 for a purpose which will 100 hereinafter appear. A cable 69 has one end anchored at 70 and this cable extends about pulleys 28, 29, 30 and 36 so as to form a block and tackle arrangement for raising the stackerhead from the position shown in 105 Fig. 2 to the position shown in Fig. 3. For the purpose of extending the stackerhead as it is being raised, extension links 71 have been provided. These links are pivoted between the upper ends of each pair of corner 110 posts and swing about the pivot 72 from the position shown in Fig. 2 to that shown in Fig. 3. Since arms 20 pivot about bolts 16 and links 71 pivot about 72 and since pivots 16 and 72 are spaced a considerable distance 115 apart, it is evident that the line joining these pivots form one side of a triangle of which the other sides are formed by the stacker arm extension frame and by links 71. When the parts are in the position shown in Fig. 2, the distance from the pivot 16 to the ends of the corresponding links 71 is a minimum, but when the parts are in the position shown in Fig. 3, this side of the triangle becomes 120 the longest. The ends of links 71 are pro- 125

130

vided with steel hooks 73, which are secured to the links and one of which extends down below the arm 20 and has an offset portion 74 that engages underneath this arm. The part 74 serves to hold the links from jumping or from leaving the stackerhead extension frame. It will be observed that hook 73 which is located on the outside of the stackerhead extension frame is the one that carries the end 74 and that the one on the inside terminates directly beneath the hook portion 75. The one on the inside has therefore been indicated by reference numeral 73a. The hooks 73 are so positioned that they will engage the pins 67 and will therefore serve to slide the stackerhead and stackerhead extension arms 45 upwardly when the stackerhead is moved from the position shown in Fig. 2 to that shown in Fig. 3. The amount of the extension depends on the position of the pin 67. When this pin is located in the hole 66 nearest to the transverse bar 67, the extension of the stackerhead is the greatest, and if it is located in the hole nearest to the stackerhead, there is practically no extension of the stackerhead and this position is therefore used when the stack is first started. As the stack increases in height, pins 67 are periodically moved closer to the bar 68 so as to extend the lift of the stacker. When the stackerhead is returned to the position shown in Fig. 2, the hook members 73 engage the transverse bars 68 so as to pull the stackerhead back to the position shown in Fig. 2.

It is, of course, necessary to provide means for limiting the throw of the stacker head and for this purpose cushion bars 76 are provided. These bars are formed each of two parallel members and have their lower ends pivoted at 77 to one end of a short link 78 whose other end is pivoted at 79 to the lower ends of the corner posts. A spring 80 has one end anchored to the cushion bars at 81 and the other anchored to the strap 13 at 82. The corner post braces are each provided with a notch 83 with which the pin 84 of the corresponding cushion bar engages when the parts are in the position shown in Fig. 2 for the purpose of holding the cushion bars in elevated position. The free end of each cushion bar is provided with a transverse pin 85, which is adapted to engage the hooked end of member 86 that is carried on the extension links 71. The length of the cushion bars is such that when the pin 85 is in engagement with the hook 86, bar 76, links 71 and posts 6 form a triangle and therefore any force tending to rotate the links 71 in a clockwise direction, puts the cushion bars under tension, instead of as would otherwise be the case, under a flexing strain. The fact that the cushion bars are under tension when they are functioning to stop the movement of the stacker head, gives a very strong construction and obviates the danger of break-

ing these bars which could easily be done if they were put under a bending strain. When the parts approach the position shown in Fig. 3, the upper ends of the extension links 71 engage the ends of the bumper springs 48 which yield under the force to which they are subjected and relieves the parts from the severe strains to which they would be subjected if these springs were not present. Attention is called at this point to the fact that when the bumper springs come in contact with the upper ends of the extension links the force exerted by the spring against the link tends to lift the stackerhead and to remove the strains from the pivots about which the stackerhead frame rotates. This is of great importance and is considered a radical departure from the usual practice which, as a rule, employs a tension member anchored at one end to the runners 3 and at the other to the stackerhead lifting frame arms 20 as with such a construction there is a resultant force which adds to the weight of the stacker arms and increases the strain on the pivots. The weight of the cushion bars 76 is added to the effect of the spring 80 and the latter force is therefore augmented to the extent of the weight of these bars.

Attention is called to the fact that the washers 14 which are provided with the hubs about which the stacker frame rotates is located some distance above the bottom of the runners 1 and therefore the stacker frame and the stacker head will be downwardly and forwardly inclined in the manner shown quite clearly in Fig. 2, which makes it possible for the ends of the bars or teeth 58 to come in contact with the surface of the ground. The stacker extension frame pivots are also located some distance from the rear end of the frame, or from the corner post 16 and as a result of this the stacker frame will have a rearward inclination when in its elevated position and this makes it possible to deposit the hay more nearly in the center of the stack than if the stacker frame was limited to a vertical position only.

From Fig. 4 it will be seen that on account of the construction employed in this stacker, the lifting arms 20 of the stacker extension frame, as well as the inclined braces 7, lie directly over or in the same plane as the runners 1, thereby obviating any twisting strains such as would be produced if the bars 20 were located on the outside of the braces 7.

Applicant desires to call particular attention to the following features of the construction:

(1) The relationship and relative lengths of the cushion bars 76, the extension links 71 and the distance between pivots 72 and 79, together with the position of hook 86, as these parts form a stop for the stackerhead lifting frame in which the cushion bars 76 are put under tension due to the fact that the

parts mentioned interconnect so as to form a triangle in which 76 is a tension member.

(2) The use of the washers 14 which are provided with hubs 15 through which the bolt 16 passes. Hubs 15 form the pivots and when bolt 16 is under tension the clamping action prevents brace 7 from splitting.

(3) The construction shown in Fig. 6 by means of which it is possible to adjust the axial plane of arm 20 and resist splitting strains from splitting this arm. This construction also distributes the tension in bar 36 so as to obviate to the greatest extent injurious strains.

(4) The presence of the buffer springs 48 which engage the upper ends of the extension links 71 when the stackerhead extension frame approaches its upper limit of movement. The force exerted by the ends of links 71 against the springs 48 tends to lift the stacker head extension frame and decreases the strains on the pivots formed by hubs 15.

(5) The interconnection of links 71 with arms 20 by means of the bent ends 74 of the hooked members 23 prevent the links from jumping off the arms, prevents accidents and assures positive operation, and

(6) The cushion bars 76 besides serving as a tension member of the triangle forming the stop also serve as cushioning means tending to oppose a gradually increasing force to the rearward motion of the stackerhead lifting frame; this is due to the action of the spring and to the action of the weight of the cushioning bars which cooperates with the spring to bring the lifting frame to a gradual stop.

Having described my invention what I claim as new is:

40 1. A stacker having a pivoted stackerhead lifting frame, means for moving said frame towards vertical position, and means for limiting the rearward movement of the lifting frame, said last named means comprising three members adapted to form a rigid structure when moved to a given position, and means carried by one of said members for engaging the stackerhead lifting frame when the latter approaches its limit of travel and 50 form a stop.

55 2. In a stacker having a supporting frame, a stacker head lifting frame pivotally attached thereto, means for rotating the lifting frame comprising an A-frame pivoted at its base to the supporting frame and tension bars connected with the upper end of the A-frame and at their lower ends with the lifting frame, the lifting frame having a transverse bar (41) whose ends are connected with 60 the two arms (20) of the lifting frame by means of bolts (43), a guide bar (44) located on each side of each of the arms, an eye bolt (39) extending through the arm and through the two guide bars, said bolt having nuts (56, 57) for clamping the guide bars against

the sides of the arms, a brace member (51) connected with the transverse bar adjacent the inside of each arm, the eye of eye bolt lying above the brace bar and connected with the brace bar and with the transverse bar by means of a bolt (53), that portion of the eye bolts between the inside of the lifting frame arms and the outside of the brace bars (51) serving as the attaching means for the tension bars (38).

70 3. A stacker having a supporting frame, a stacker head lifting frame having two parallel arms pivoted at one end to the supporting frame and means for twisting the arms.

75 4. A stacker having a supporting frame, a stacker head lifting frame having two parallel arms pivoted at one end to the supporting frame, a transverse bar extending between the arms and secured to the under side of the latter, and a bolt extending through each arm near the center thereof, said bolts having one end anchored to the transverse bar and provided with a nut on each side of the arm whereby when the nuts are manipulated the arm can be moved along the bolt and twisted.

80 5. A stacker having a supporting frame, a lifting frame having one end pivoted to the supporting frame, means for rotating the lifting frame from a substantially horizontal to a substantially vertical position, a link pivoted to the supporting frame at a point above and to the rear of the lifting frame pivot, means carried by the free end of the link for slidably connecting it with the lifting frame and a spring carried by the lifting frame and so located that it will engage the end of the link when the frame approaches the limit of its upward movement.

85 6. In a stacker having a supporting frame having spaced runners and provided with a corner post at each rear corner, a brace extending diagonally from the top of each corner post to the corresponding runner, a support extending from the lower side of each brace to the corresponding runner, said brace and support having their ends notched into the runner, connecting strap extending from each side of the brace to the runner, connecting straps for connecting the support to the runner, means for connecting the upper end of the support with the brace, a washer secured to each side of the brace, each of said washers having a central hub, a bolt extending through the brace and through the washers and a lifting frame having one end pivoted to the hubs of said washers.

90 7. In a stacker having a supporting frame having spaced runners and provided with a corner post at each rear corner, a brace extending diagonally from the top of each corner post to the corresponding runner, a support extending from the lower side of each brace to the corresponding runner, said brace

and support having their ends notched into the runner, connecting strap extending from each side of the brace to the runner, connecting straps for connecting the support to the runner, means for connecting the upper end of the support with the brace, a washer secured to each side of the brace, each of said washers having a central hub, a bolt extending through the brace and through the washers, a lifting frame having one end pivoted to the hubs of said washers and means for rotating the frame about its pivots.

In testimony whereof I affix my signature.
JOSEPH H. COPE.
